UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REVERSING APPARATUS FOR HEATING FURNACES.

Application filed July 28, 1922. Serial No. 578,221.

To all whom it may concern:

Be it known that I, GEORGE H. ISLEY, a citizen of the United States, residing at Worcester, in the county of Worcester and

- 5 Commonwealth of Massachusetts, have invented a new and useful Improvement in a Reversing Apparatus for Heating Furnaces, of which the following, together with the accompanying drawings, is a specification.
- 10 The present invention relates to improvements in the apparatus which is used with the regenerative type of furnaces, for reversing the course through such a furnace of the burning gaseous fuel.
- 15 The present invention embodies the adaptation of certain principles of operation which characterize the reversing apparatus forming the subject matter of my United States Letters Patent No. 1,408,946, issued
- 20 March 7, 1922. The present invention contemplates the introduction of novel and improved features in apparatus of this class, whereby to render the same adaptable to heating furnaces, soaking pits and the like, including open hearth furnaces and other types, to which the air for supporting combustion of the fuel is admitted under pressure,—instead of being drawn in from the atmosphere. Other and further improvements, in connection with the operating devices for such reversing apparatus, will be apparent as the description proceeds, reference being had to the accompanying drawings, wherein—

35 Fig. 1 is a diagrammatic view illustrating the application of my invention to a regenerative furnace adapted to operate with air under pressure.

40 Fig. 2 is a top plan view of one of the units of the reversing apparatus.

Fig. 3 is a vertical sectional view along the line 3, 3 of Fig. 2, and

45 Fig. 4 is an enlarged view in side elevation, partially in section, of a hydraulic operating device for one of the reversing units.

Fig. 5 is a vertical sectional view of a modified form of the invention.

50 Fig. 6 is a diagrammatic view similar to Fig. 1, illustrating the application of said modified form to a regenerative furnace.

Like reference characters refer to like parts in the different figures.

Referring to Fig. 1, the furnace is indicated diagrammatically at 1, the same being provided at opposite ends with the usual gas regenerator passages 2 and 2' and the usual air regenerator passages 3 and 3'. Each gas regenerator 2, 2' is in communication with an underground flue 4 and said flues 4, 4 have their terminals 5, 5 at opposite ends of the furnace, adjacent to similar terminals 6, 6 of gas supply flues 7, 7.

In the same way each air regenerator passage 3 and 3' is in communication with an underground flue 8 and these flues 8 have terminals 9, 9 at the ground level which are adjacent to the terminals 10, 10 of air supply flues 11, 11, the latter being connected to any suitable source of air under pressure, not shown.

In alignment with each pair of flue terminals 5, 6, is the terminal 12 of an underground flue 13 and these two flues 13, 13 merge into a common stack flue 14, as shown in Fig. 1. Each flue 13 has an intermediate upwardly directed branch whose terminal 15 is in line with the terminals 9 and 10 and thus at each end of the furnace there is a group of six flue terminals, each group being composed of two rows of three terminals each, namely, 5, 6, 12 and 9, 10, 15.

Each group of the six flue terminals is surmounted by a water seal pan or base 16, the latter providing suitable flanged openings in registry with said terminals, and maintaining a supply of water, for sealing purposes, in surrounding relation to all of said openings. In cooperation with each group of six terminals is provided a reversing unit for each end of the furnace; these

reversing units are identical in construction and a description of one will suffice for both. Each unit comprises a pair of shiftable hoods 17, 18, the former cooperating with the flue terminals 5, 6 and 12 and the latter cooperating with the flue terminals 9, 10 and 15. The hoods 17, 18 of each unit are connected to move in unison by means of cross bars 19, 19 which engage with lugs or ears 20, 20, secured to opposite ends of said hoods. The cross bars 19, 19 are themselves supported, between the hoods, by pivoted links 21, 21 as shown in Figs. 2, 3 and 4, said links 21 being dis-

posed for swinging movement with respect to their pivots or trunnions 22, 22 on a pair of stationary opposed hydraulic cylinders 23, 23'. The latter preferably occupy the space in the water pan or casing 16 which separates the row of terminals 5, 6, 12 from the row of terminals 9, 10 and 15.

A double acting plunger rod 24 works in the two opposed cylinders 23, 23'; intermediate said cylinders, this plunger rod has secured thereto a cross head 25 having a pivoted connection 26 with one of the sets of links 21. When water is admitted to the right hand cylinder 23, Fig. 4, by way of a feed pipe 27, the plunger rod 24 is driven to the left, and by its above described connection with the supporting links 21 of the hoods 17 and 18, the latter are shifted, in the same direction, being constrained by the links 21 to have a parallel motion of translation which carries them upwardly from the position shown in Figs. 2 and 3, and then downwardly into their other position where they cover, connect and seal the terminals 5, 12 and 9, 15 respectively. Starting from this left hand position, when water is admitted to the left hand cylinder 23', Fig. 4, by way of supply pipe 27', this motion is reversed,—the two hoods 17 and 18 returning to the positions illustrated in Figs. 2 and 3, where, as shown, they cover, connect and seal respectively the terminals 5, 6 and the terminals 9, 10, respectively.

This sealing of the two terminals which are spanned by each hood 17, 18 is effected by means of a depending skirt or apron 28, the latter dipping into the water of the pan 16 and completely surrounding the flanges that correspond to the adjacent terminals. Each gas supply terminal 6, and each air supply terminal 10, is equipped with a gravity acting swinging closure 29, the latter having a transverse trunnion 30 which finds bearing in suitable slots provided by a bracket or ear 31 of the base casing 16. Each closure 29 has a projecting lug 32 for cooperation with the skirt or flange 28 of the superposed hood 17 or 18, and in the position of the parts shown in Fig. 3 said flange 28, by contact with said lug 32, holds the closure 29 in raised position; this permits the flow of gas from flue 7 into flue 4 by way of hood 17, and in a like manner the flow of air under pressure from flue 11 into flue 8 by way of similarly disposed hood 18. The reversing unit at the left hand side of Fig. 1 occupies the position above described, the hood 17 spanning the terminals 5, 6, as shown in Fig. 3, and the hood 18 being similarly disposed relative to the terminals 9, 10, thus causing the gas and air under pressure to enter the furnace through the regenerator passages 2 and 3. It is to be noted that in this position of the parts, the terminals 12 and 15 at the left hand side of

the furnace are shut off and sealed by means of covers 33, the latter being pivoted at 34 to the respective hoods 17 and 18.

At the right hand side of the furnace, Fig. 1, the other reversing unit constituted by the two hoods 17 and 18 is shown in the opposite position, namely, with the hood 17 spanning the flue terminals 5, 12 and the hood 18 spanning the flue terminals 9, 15. As a consequence of this, the gravity closing covers 29 of the right hand terminals 6 and 10 are released, and thereby seal the said terminals against the passage of gas and air under pressure from the flues 7 and 11, respectively. The products of combustion from the furnace issuing at the right hand side thereof through the regenerator passages 2' and 3' are conveyed by the flues 4 and 8 to the terminals 5 and 9, passing by way of hoods 17 and 18 to the terminals 12 and 15, and thence into the right hand flue 13 leading to the stack passage 14.

The reversal of the furnace is effected by causing the two units to move in opposite directions. When the hoods 17 and 18 of the right hand unit are swung over to uncover the terminals 12 and 15 and to cover the terminals 6 and 10 the following action is observed:—the covers 33 which previously had occupied the dotted line position shown in Fig. 3 on account of their attachment to cords 35, swing down by gravity into sealing position over the right hand terminals 12 and 15. At the same time the act of spanning the terminals 6 and 10 by this right hand set of hoods 17, 18, procures the elevation of the closures 29, 29, thus establishing the flow of gas and air under pressure into the regenerator passages 2' and 3'. At the left hand side of the furnace, the reverse movement of the hoods 17 and 18 procures the gravity shut off, by closures 29, 29, of the terminals 6 and 10, and at the same time removes the covers 33, 33, from the terminals 12 and 15, said covers assuming the tipped-up position shown in Fig. 3, by reason of their attachment to the cords 35. This action permits the flow of combustion products from the regenerator passages 2 and 3 by way of flues 4 and 8 and hoods 17 and 18 into the right hand flue 13 and thence to the stack passage 14.

In another form of the invention, illustrated diagrammatically in Fig. 6, the gas regenerator passages 2 and 2', and the air regenerator passages 3 and 3' of the furnace are respectively, in communication with individual flue terminals 36, 36, and 37, 37, the same forming part of two aligned rows of six flue terminals each, namely, gas supply terminals 38, 38, air supply terminals 39, 39 and stack flue terminals 40, 40, and 41, 41. By means of suitable underground flues, the four stack terminals, two in each row, are connected to a common stack passage 42.

The terminals 38 and 39 of each row are associated respectively with a gas supply flue 43 and with a supply flue 44 conveying air under pressure from any suitable means, not shown.

Each group or row of six flue terminals is surmounted by an elongated water-seal pan or base 45, the latter providing suitable flanged openings in registry with said terminals, and maintaining a supply of water for sealing purposes in surrounding relation to all of said openings. In cooperation with each group of six terminals, is provided a reversing unit for each end of the furnace; 10 these reversing units are identical in construction and a description of one will suffice for both. Each unit comprises a pair of longitudinal alined shiftable hoods 46, 47, the former cooperating with the flue terminals 41, 37, 39, and the latter cooperating with the flue terminals 40, 36, 38. The hoods 46, 47, of each unit are connected to move in unison by means of a framework 48 rigidly secured to the sides of said hoods, and 20 maintaining them in spaced relation so as always to leave between them a single flue terminal (either the terminal 39 or the terminal 40) which is covered and sealed by a plate 49.

30 The framework 48, carrying the hoods 46, 47, and the connecting plate 49, is capable of a parallel motion of translation by reason of its pivotal attachment at 50, 50, to swinging parallel links 51, 51, projecting upwardly from the base 45. The specific means employed to effect this movement is wholly independent of the present invention; any suitable actuating devices may be utilized, such for instance as disclosed in my copending application, Serial No. 268,391, filed Dec. 26, 1918. It is sufficient to note that each gas supply terminal 38 in the present arrangement is equipped with a gravity actuating swinging closure 51, having a projecting lug 52 for cooperation with the sealing skirt or flange 53 of the hood 47, and that each hood 46 has pivoted thereto a cover 54 adapted in one position of the reversing unit to shut off and seal the stack flue terminal 41.

55 As indicated in Fig. 6, wherein the right hand reversing unit occupies the position shown in Fig. 5, the direction of gaseous products through the furnace is from right to left, the gas entering the regenerator 2' by way of hood 47 of the right hand unit, and the air under pressure entering the regenerator 3' by way of hood 46 of the right hand unit; the two stack terminals 40 and 60 41 of the right hand group are shown as blanked off, the former by the plate 49, and the latter by the cover 54. At the left hand end of the furnace, as shown in Fig. 6, the reversing unit occupies its other position, having been shifted to expose the gas supply

terminal 38, which latter remains sealed off by its gravity closure 51. At this end of the furnace the burned products of combustion issuing from regenerator 2 pass into stack terminal 40 by way of hood 47, and 70 the burned products of combustion issuing through regenerator 3 pass into stack terminal 41 by way of hood 46; the cover 54 of this unit is inoperative, and the air supply terminal 39 is blanked off by the connecting 75 plate 49.

The reversal of the furnace is effected by causing both units to move to the left, Fig. 6. This, as will be well understood, disposes the left hand unit in the same relative position to its group of terminals as shown in 80 Fig. 5, thus connecting the regenerators 2 and 3 with the sources respectively of gas and air under pressure; at the right hand side the sources of gas and air under pressure are blanked off, and the regenerators 2' and 3' are connected to stack. It is to be noted, in both forms of the invention, that the closures 29 and 51 associated with flue terminals 6, 10 and 38, and controlling the 85 passage of ingoing comparatively cool gases to the furnace, can open within the hoods 17, 18 and 47 without danger of being overheated by the gases passing through said hoods. On the other hand, the covers 33 and 90 54, associated with terminals 12, 15 and 41, are so arranged as not to be enclosed by the hoods at any time, since said covers are subject, when in a lowered position, to the intense heat of the burned gases, and hence, at 95 other times must be left exposed to the cooling action of the atmosphere.

I claim,

1. The combination with a regenerative furnace wherein combustion is supported by 105 air under pressure, of reversing apparatus for said furnace constituted by duplicate pairs of uninclosed hoods at each end.

2. The combination with a regenerative furnace wherein combustion is supported 110 by air under pressure, of reversing apparatus for said furnace constituted by duplicate pairs of uninclosed hoods, each pair providing for the inflow of air under pressure and gas and for the outflow of combustion 115 products.

3. The combination with a regenerative furnace having for each end a supply of air under pressure, and a supply of gas, of reversing means for said furnace constituted 120 by duplicate pairs of uninclosed hoods, each pair adapted to control the flow to said furnace of gas and of air under pressure.

4. The combination with a regenerative furnace having for each end a supply of air under pressure, and a supply of gas, of 125 cooperating duplicate reversing devices, one for each end of the furnace, and each consisting of a pair of uninclosed hoods, side by side, and movable in unison. 130

5. The combination with a regenerative furnace having for each end a supply of air under pressure, and a supply of gas, of co-operating duplicate reversing devices, one for each end of the furnace, and each consisting of a pair of uninclosed hoods, side by side, with a common interposed actuating means:

6. The combination with a regenerative furnace having for each end a supply of air under pressure, and a supply of gas, of co-operating duplicate reversing devices, one for each end of the furnace, and each consisting of a pair of uninclosed hoods side by side, and movable in unison, one serving for the inflow of air under pressure and the other serving for the inflow of gas.

7. The combination with a regenerative furnace having for each end a supply of air under pressure, and a supply of gas, of co-operating duplicate reversing devices, one for each end of the furnace, and each consisting of a pair of uninclosed hoods side by

side, and movable in unison, said hoods in one position serving independently for the inflow of air under pressure and gas, and cooperating, in another position, to handle the outflow of combustion products. 25

8. The combination, with a regenerative furnace, of reversing means therefor, consisting of duplicate movable devices at each end, each device providing a pair of uninclosed hoods, side by side, for cooperation with the gas, air, regenerator and stack flues of the furnace. 30

9. The combination with a regenerative furnace having for each end a supply of air under pressure, and a supply of gas, of co-operating duplicate reversing devices, one for each end of the furnace, and each consisting of a pair of uninclosed hoods movable in unison, one serving for the inflow of air under pressure and the other serving for the inflow of gas. 40

GEORGE H. ISLEY.
